(57) **CLAIM**

The ornamental design for a container for medical use as
shown and described.

DESCRIPTION

FIG. 1 is a perspective view of container for medical use,
showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in FIG. 7 illustrate portions of the
container for medical use that form no part of the claimed
design.

1 Claim, 7 Drawing Sheets
